UNITED STATES PATENT OFFICE.

ALFRED ANGERS, OF BLACK LAKE, QUEBEC, CANADA.

ASBESTOS-FIBER SEPARATOR.

1,419,437.

Specification of Letters Patent. Patented June 13, 1922.

Application filed June 18, 1921. Serial No. 478,672.

To all whom it may concern:

Be it known that I, ALFRED ANGERS, a subject of the King of Great Britain, residing at Black Lake, in the Province of Quebec, Canada, have invented certain new and useful Improvements in Asbestos-Fiber Separators; and I do hereby declare that the following is a full, clear, and exact description of the invention, such as will enable others skilled in the art to which it appertains to make and use the same.

The present invention relates to new and useful improvements in an asbestos fiber separator.

15 The primary object of the invention is the provision of a machine for the separation and extraction of asbestos fiber from the tails after the tailing-screens in order to make a further use of material, which ordinarily goes to waste.

Another object of the invention, is the provision of a machine of the above specified type, so constructed that when the material, which ordinarily goes to waste passes 25 through the machine, a certain amount of asbestos fiber, will be extracted therefrom, for further use.

Another object of the invention, is the provision of a machine of the above specified type, including a hopper, and a compartment through which the material passes, the said compartment being provided with 30 means for separating the fiber from the remaining waste material, and extracting it 35 from the machine, for further use.

A still further object of the invention, is the provision of a machine of the above specified type, which will be comparatively simple and inexpensive to manufacture, reliable and efficient in use, and readily operated.

With the above and other objects in view, the present invention resides in the novel features of construction, formation, combination, and arrangements of parts, to be hereinafter more fully described, claimed, and illustrated in the accompanying drawing, forming a part of the present application; and in which;

50 Figure 1 is a longitudinal sectional view, taken through the invention; and,

Figure 2 is a transverse sectional view, part of the machine being shown in elevation.

55 Referring now to the accompanying draw-

ing, by corresponding characters of reference, throughout the several views, the numeral 5 designates in general my improved asbestos fiber separator, which consists of a substantially rectangular housing 6, comprising the front and rear walls 7 and 8, the opposite side walls 9, a bottom 10 and a top 11.

The housing 6 is provided with a pair of vertical partitions 12, which separate the same into a central and opposite side compartments 13 and 14 respectively.

The bottom 10 is provided with an opening 15, which communicates with the compartment 13, through which the waste material is discharged.

70 The top 11 is likewise provided with an opening 16, which communicates with the compartment 13, and in which is disposed, the lower end of a hopper 17 into which is fed the waste material from the tailing-screen, of any well known separator (not shown in the drawing).

75 A feed roller 18, is mounted below the hopper 17 and disposed at one side thereof are a plurality of fingers 19, which co-operate, with the roller by feeding the contents slowly into the upper end of the compartment 13.

80 A plurality of downwardly inclined frames 20 are mounted upon opposite sides of the compartment 13, as shown in Figure 1 of the drawing.

85 Baffle plates 21 are adjustably mounted upon the frames 20, in order to regulate the space, through which the contents of the hopper 17 flows.

90 Co-operating plates 22, which are likewise inclined downwardly, are secured to the partitions 12 adjacent the free ends of the baffle plates 21, and these plates may be hingedly mounted and serve to retard the flow of the contents through the compartment 13, from its upper end to its lower end.

95 Openings 23 are formed in the partitions 12 below the plates 22 and the material at the lower end of the opening is inclined upwardly, in a direction opposite to that of the plates 22. These openings provide passages through which the fiber is adapted to be drawn in a manner to be hereinafter described.

100 Plates 25 are secured to the lower ends of the partitions 12, and to the upper ends of the side walls 9, forming passages through which the fibrous material is sucked

by the pipes 26, which extend through the top 11 into the upper end of the compartments 14.

In operation the material is fed into the 5 hopper 17, from which it passes downwardly through the compartment 13, striking the baffle plates 21 and 22, which retard its movement and after passing below the baffle plates the suction through the pipes 26 and 10 27, draws the fibrous material upwardly through the openings 22, and discharges it to any desired locality. The material passing through the opening 15 at the lower 15 end of the housing 6, is the waste material which may be carried to any desired locality, for dumping purposes.

From the foregoing description taken in connection with the accompanying drawing, it will be manifest that a separator for asbestos fiber is provided which will fulfil all of the necessary requirements of such a device, eliminating any waste in the machines now in common use, and it should be understood in this connection, that various 25 minor changes in the specific details of construction, can be resorted to within the scope of the appended claims, without departing from the spirit or sacrificing any of the advantages of the invention.

30 Having thus fully described this invention, what I claim as new and desire to secure by Letters Patent is:

1. In a machine of the character described, the combination of a housing, partitions 35 located within said housing, and dividing the latter into central and side compartments, said partitions having openings therein, providing communication between

the central and side compartments, plates secured to the inner side of the central compartment above the openings and inclined downwardly, baffle plates arranged in staggered relation, and extending toward the ends of the first mentioned plates, suction pipes extending into the side compartments, at the upper end thereof, and inclined plates leading from the lower end of the partitions to the upper end of the side compartments, substantially as, and for the purposes set forth. 40 45 50

2. In a machine of the character described, the combination of a housing, partitions located within said housing and dividing the latter into central and side compartments, said partitions having openings therein, providing communication between the central and side compartments, plates secured to the inner side of the central compartment above the openings and inclined downwardly, baffle plates arranged in staggered relation 60 and extending towards the ends of the first mentioned plates, means for adjustably supporting said baffle plates, suction pipes extending into the side compartments, at the upper end thereof, and inclined plates leading from the lower end of the partitions to the upper end of the side compartments, substantially as and for the purposes set forth. 55 65

It witness whereof I have hereunto set 70 my hand.

ALFRED ANGERS.
